UNITED STATES PATENT OFFICE.

JACOB I. ROBIN, OF HARROW, ENGLAND.

APPARATUS FOR TREATING INCANDESCENT MANTLES.

1,259,556.

Specification of Letters Patent. Patented Mar. 19, 1918.

Application filed July 6, 1914, Serial No. 849,045. Renewed January 28, 1918. Serial No. 214,247.

To all whom it may concern:

Be it known that I, JACOB IGNOT ROBIN, a citizen of the United States, residing at town of Harrow, county of Middlesex, England, have invented certain new and useful Improvements in Apparatus for Treating Incandescent Mantles, of which the following is a full, clear, and exact description.

My invention relates to an apparatus for 10 treating incandescent mantles, by which I mean mantles used for incandescent burners of various kinds, and has for its object to provide a simple and efficient means for applying stiffening liquids to such mantles. 15 It further has for its object to provide an apparatus which is automatic in its action and produces a uniform result.

The following is a description of my invention, reference being had to the accompanying drawings, in which—

Figure 1 shows, partly in front elevation and partly in section, a machine embodying my invention;

Fig. 2 shows a plan view of the machine, 25 parts being broken away on the line 2—2, Fig. 1.

Figs. 2^a and 2^b show an elevation and section of a modified distender mounted on the machine spindle;

Fig. 3 shows a transverse section of the same on the line 3—3, Fig. 1, looking toward the left;

Fig. 4 shows a transverse section of the machine on the line 4—4, Fig. 1, looking 35 toward the left;

Fig. 5 shows a transverse section of parts of the machine on the line 5—5, Fig. 1, looking toward the right;

Fig. 6 shows a detail of gearing;

Fig. 7 shows a plan view of a holder forming part of the machine;

Fig. 8 shows a similar view of the holder with the parts in different position;

Fig. 9 shows a section of the holder on 45 the line 9—9, Fig. 7.

Referring more particularly to the drawing, 1 is the base of the machine having a frame consisting of uprights 2, a top plate 3, and bearings 4—4. Depending from the 50 top plate are bearings 5—5 in which is mounted the main shaft 6. This main shaft is provided with a mutilated gear 7 and a complete gear 8, the latter of which engages with an intermediate gear 9, which in turn 55 engages with the gear 10 on a shaft 11 carrying at each end a spindle 12 provided with

a friction spring 13. The shaft 11 is also provided with adjustable collars 14.

Upon the spindles 12 are mounted holders consisting of a base plate 15 having recesses 16 and a tubular extension therefrom 17. This tubular extension is provided with a yielding end piece 18 which is held in extended position by spring 19, its outward movement being limited by the pin 19'. Surrounding the base of the holder is a ring 20 having recesses 21 and carrying a stop 22 which limits its movement of rotation about the base 15. The exterior of the base 15 and the interior of the ring 20 are provided with screw threads 23 which serve to hold the ring upon the base.

Mounted on the top plate is a movable plate 24 carrying two nozzles 25, the discharge openings of which are directed toward the holders. These nozzles as shown are atomizing nozzles and act to convert the stiffening fluid supplied thereto into a stream of finely divided liquid. 26 is a container for the stiffening liquid supported 80 by a bracket 26'. 27 is a pipe leading therefrom to a manifold 28 from which lead tubes 29 to chambers 30 of the nozzles. The passage of fluid from this chamber is controlled by a needle valve 31. The spring 32 bearing against a shoulder 33 normally tends to hold this needle valve closed. A lever 34 pivoted at 35 when moved to the position shown in dotted lines, Fig. 4, opens the needle valve permitting the liquid to discharge. The container 26 of liquid to be applied is above the nozzle, so that the liquid is fed to the nozzle by gravity, being applied to the mantle under pressure by compressed air preferably directed as shown. 95

Surrounding the chamber 30 is a passage 36 which is connected by a pipe 37 to an air valve 38 which controls gas such as air led by the pipe 39 from any convenient source of compressed air or other gas. Mounted 100 upon the shaft 6 is a cam 40 which acts upon a lever 41 which in turn acts upon the rod 42 of the air valve so that when the cam is in the position shown in Fig. 3, the air valve is closed while when in the position 105 shown in dotted lines Fig. 3, the air valve is opened. Mounted upon the main shaft 6 are two other cams 43 which control the liquid supply by actuating the needle valves. These cams when in the position shown in 110 Fig. 3, permit the liquid supply to be cut off. When turned from that position, they en-

gage slides 44 which are provided with adjustable abutments 45. These abutments are normally clamped upon the slides in definite positions and when the slides 44 are forced to the rear and engage the lower ends of the levers 34 so as to move the needle valves 31 backward against the action of their springs 32 so as to open the liquid discharge openings of the nozzles. The cams 40 and 43 are so shaped and timed that the cam 40 opens the air valve before the cams 43 open the liquid valves. The cam 40 also maintains the air valve open until after the cams 43 have permitted the liquid valves to close.

The inner ends of the mantles 46 surround distenders 47, which in the form shown in Fig. 1, while permanently attached to the mantle perform the function of holding the lower ends of the mantles in shape to be treated, and coöperate with the other elements of the machine. These distenders are provided with three radial projections 48, which are useful in supporting the distender and with it the mantle when in use in the burner, and also serve to hold the distender to the holder in the form shown. In mounting the mantle upon the holder these radial projections of the distender are inserted in the recesses 21 of the ring 20 with the parts in the position shown in Fig. 7. The ring 20 is then turned to the position shown in Fig. 8, thereby clamping the distender and mantle to the holder. As the radial projections 48 are being passed through the openings 21 of the ring 20, the movable end 18 of the holder is depressed against the action of the spring 19. When the distender 47 is secured in position and the upper end 18 of the holder is released, the spring 19 acts to force the end 18 outward and put the mantle under a slight tension and to extend it longitudinally, causing it to assume the shape shown in Fig. 1.

The plate 24 which carries the nozzles is movable forwardly and rearwardly upon the plate 3 and can be held in adjusted position by the thumb screws 49. It is also provided at each end with an index 50 moving over a scale 51 to aid in adjusting the position of the plate 24.

Suspended from the top plate as shown in Fig. 5 is a worm 52 on the shaft of which is mounted a pulley 53 driven by a belt 54 from any convenient source of power. A loose pulley 55 is also mounted upon the shaft of the worm. The worm meshes with a worm wheel 56 which is connected to a gear 57 in line with the mutilated gear 7 above referred to. The shaft 6 is provided with a crank or other manual device 58 so that it together with the gear 7 can be given a slight turn sufficient to bring the teeth of the mutilated gear 7 into engagement with the teeth of the gear 57.

Instead of the distender connected to the mantle a separate distender 47', such as shown in Figs. 2^a and 2^b, may be used. In such case the distender 47' is placed upon the spindle, and the skirt of the mantle being placed thereon, treated with the fluid. Preferably these distenders 47' are made separable from the spindles so that the holders above described may be substituted therefor when desired.

The operation of the apparatus is as follows. The nozzles are first adjusted at the proper distance from the mantle by moving the plate 24 and securing it in proper position. This affects the relation of the lever 34 to the slide 44 and the movable abutments 45 may have to be adjusted so as to make the cams 43 open the needle valves 31 to the proper degree. After these adjustments have been made, a mantle, together with its distender 47, is mounted upon one or both of the holders. The handle 58 is then given a slight forward movement sufficient to bring the teeth of the mutilated gear 7 into engagement with the teeth of the gear 57, 90 this gear being continuously revolved by the power applied through the worm 52. This causes the gear 8 to revolve the spindles carrying the mantles, whereupon the cam 40 opens the air valve after which the cams 43 open the needle valves, whereupon streams of stiffening fluid under pressure are produced directed toward the mantle. The action continues until, with the gearing shown, the mantle has revolved twice, whereupon 100 the cams 43 permit needle valves to close and shut off the liquid, after which the cam 40 permits the air valve to close and cut off the air. At a later period the mutilated part of the gear 7 reaches the gear 56 with 105 the result that the holders together with the mantles stop rotating and the machine, except for the idle action of the worm 52, is at rest. The holders are then removed and other holders having mantles and distenders 110 47 mounted thereon are substituted and after another forward movement of the crank 58 the action is repeated. When the distender 47' is used the holder is omitted.

From the foregoing it will be seen that in 115 carrying out the process with the apparatus above referred to, a mantle is first distended and then rotated about its axis. During such rotation liquid under pressure is discharged and applied thoroughly impregnates the material of the mantle in a narrow belt and enables the obtaining of a uniform and perfect product.

If desired, the worm 52 also may be 125 stopped by shifting the belt 54 from the fast pulley 53 to the loose pulley 55 by means of the belt shifter 59.

As will be evident to those skilled in the art my invention permits of various modifi- 130

cations without departing from the spirit thereof or the scope of the appended claims.

What I claim is:

1. In an apparatus for applying bands of stiffening fluid to incandescent mantles, the combination of a distender for the mantle to be treated, a nozzle, means to apply to said mantle liquid issuing from said nozzle, and means for producing a relative rotary movement between said nozzle and said distender.

2. In an apparatus for applying bands of stiffening liquid to incandescent mantles, the combination of a distender for the mantle to be treated, a nozzle means for applying to said mantle liquid issuing from said nozzle, and means for revolving said distender.

3. In an apparatus for treating incandescent mantles with liquid, the combination of a distender for the mantle to be treated, a nozzle, means for applying to said mantle liquid issuing from said nozzle, means for producing a relative rotary movement between said nozzle and said distender, and means for automatically stopping said movement and the action of said nozzle.

4. In an apparatus for applying stiffening fluid to incandescent mantles, the combination of a distender for the mantle to be treated, a nozzle, means for applying to said mantle liquid issuing from said nozzle, means for producing a relative rotary movement between said nozzle and said distender, and means for varying the amount of liquid from said nozzle.

5. In an apparatus for applying stiffening liquid to incandescent mantles, the combination of a distender for the mantle to be treated, means for rotating the same, a nozzle, a source of stiffening liquid, an air supply causing a spray to issue from said nozzle, means for cutting off said source and said air supply from said nozzle, said rotating means and said cutting off means being actuated from the same source of power.

6. In an apparatus for treating incandescent mantles, a holder consisting of a recessed base plate, an extension therefrom, a movable end piece for said extension, a spring for holding said movable end piece yieldingly in outward position, a revolute holding plate having a plurality of recesses adapted to be moved into and out of registry with recesses in said base plate.

7. In an apparatus for treating incandescent mantles with liquid, the combination of a frame, a main shaft and spindle mounted therein and geared together, said spindle being adapted to carry the mantle to be treated, a nozzle for applying liquid to such mantle, valves for said nozzle, and cam means mounted upon said main shaft for controlling said valves.

8. In an apparatus for treating incandescent mantles, the combination of a frame, a main shaft and a spindle mounted therein and geared together, said spindle being adapted to carry the mantle to be treated, a nozzle for applying liquid to such mantle, an air valve and a liquid valve controlling ducts leading to said nozzle, and cams mounted upon said main shaft for controlling said valves.

9. In an apparatus for treating incandescent mantles with liquid, the combination of a frame, a main shaft and a spindle mounted therein and geared together, said spindle being adapted to carry the mantle to be treated, a nozzle for applying liquid to such mantle, an air valve and a liquid valve controlling ducts leading to said nozzle, and cams mounted upon said main shaft for controlling said valves, the cam controlling said air valve opening the same before the cam controlling said liquid valve is in opening position, and holding it open until after the cam controlling said liquid valve has reached closing position.

10. In an apparatus for treating incandescent mantles with fluid, the combination of a distender for a mantle to be treated, a nozzle, means for applying to said mantle liquid issuing from said nozzle, means for producing a relative rotary movement between said nozzle and said distender, comprising a mutilated gear, a complete gear meshing with the teeth thereon, a worm gear connected to said last named gear, a worm engaging said worm gear, and means for rotating said worm.

11. In an apparatus for applying stiffening liquid to incandescent mantles, the combination of a distender for the mantle to be treated, a nozzle, means for applying to said mantle liquid issuing from said nozzle, means for producing a relative rotary movement between said nozzle and said distender, comprising a mutilated gear, a continuously moving complete gear meshing with the teeth thereon, manual means for bringing the teeth of said mutilated gear into engagement with the teeth of said complete gear.

12. In an apparatus for applying stiffening fluid to incandescent mantles, the combination of a distender for the bottom of the mantle to be treated, a holder for stretching the same longitudinally, a nozzle, and means for locally applying to said mantle in proximity to said distender, liquid issuing from said nozzle.

JACOB I. ROBIN.
